CLAIM

The ornamental design for a wash basin, substantially as shown and described.

DESCRIPTION

FIG. 1 is a top plan view of a wash basin showing my new design;

FIG. 2 is a front elevational view thereof;

FIG. 3 is a left side elevational view thereof, the right side being a mirror image of the side shown;

FIG. 4 is a cross sectional view taken on line 4—4 of FIG. 1; and

FIG. 5 is a cross sectional view taken on line 5—5 of FIG. 1.

Fig. 1.

Fig. 2.

Fig. 3.

Fig. 4.

Fig. 5.
